FOOD HOLDER FOR AN ELECTRIC TOASTER OR THE LIKE

Ernest H. Domshy, 8342 E. Imperial Highway,
Downey, Calif. 90242

Filed Feb. 17, 1969, Ser. No. 15,799

Term of patent 14 years

Int. Cl. D7—04

U.S. Cl. D81—10

Fig. 1.

Fig. 2.

Fig. 3.

Fig. 4.

FIG. 1 is a perspective view of a food holder for an electronic toaster or the like showing my new design;

FIG. 2 is an end elevational view;

FIG. 3 is a rear elevational view; and

FIG. 4 is a bottom plan view.

I claim:

The ornamental design for a food holder for an electric toaster or the like, substantially as shown.
